UNITED STATES PATENT OFFICE.

AMBROSE FLEMING, OF ALEXANDRIA, VIRGINIA.

ELECTRIC IRON.

Application filed February 10, 1921. Serial No. 443,902.

To all whom it may concern:

Be it known that I, AMBROSE FLEMING, a citizen of the United States, residing at Alexandria, in the State of Virginia, have invented certain new and useful Improvements in Electric Irons, of which the following is a specification.

My invention has reference to improvements applicable to the conventional types of electric irons and primarily it has for its purpose to provide certain simple and inexpensive current controlling devices, adapted to be readily applied to the different forms of hand manipulated electric irons, for automatically cutting out the electric current when the iron is not in actual use.

As is well known to users of electric irons, when it is desired to momentarily leave the iron set or, in other words, when the user's attention is required for other purposes, unless the heating element (the electric current) is cut off, the iron becomes excessively hot, scorches or otherwise injures the article being ironed and consumes unnecessary current, causing unnecessary expense as well as danger of the articles being burned.

My invention is primarily designed to overcome the objections noted by automatically cutting off the heating element to the iron, immediately when the user releases the hand hold and which, likewise restores the electric current as soon as the user again grasps the handle of the iron for resuming the operation of ironing.

My invention further provides certain improved features, in the nature of a simple means capable of being conveniently adjusted for maintaining the circuit contacts in a closed relation without the necessity of maintaining a grip on the handle, especially when it is desired to heat up the cold iron to condition for ironing and which may be automatically released as the user grips the handle for ironing.

With other minor objects in view that will hereinafter be mentioned, my invention embodies, in current controlled devices for electric irons, the peculiar features of construction and novel combination of parts, fully explained in the following detailed description, as specifically stated in the appended claims and illustrated in the accompanying drawing, in which:—

Figure 1 is a side elevation of an electric sad iron with my improvements operatively applied thereto.

Figure 2 is a detail central longitudinal section of a portion thereof, on a somewhat enlarged scale, the operative or circuit closed position of the parts being shown in full lines and the inoperative current circuit open or broken position being indicated in dotted lines.

Figure 3 is a detail vertical section taken on the line 3—3 of Figure 2.

Figure 4 is a detail perspective view of the switch lever, per se.

Figure 5 is a detail cross section of a portion of the sad iron handle and the auxiliary handle portion that is cooperative with the said handle.

Figure 6 is a detail section of the auxiliary handle pivot connection hereinafter specifically mentioned.

My invention has special reference to an improved construction of the plug connection that joins the body of the iron with the electric current cord which connects with an electric or current supplying socket since practically no change of the iron proper is necessary, excepting in the wooden hand hold 1 that is formed with a narrow slot or socket 2 that extends the full length along the bottom thereof and which is preferably fitted with a l-shaped metal liner 3 to provide smooth side faces for the socket, the purpose of which will be presently explained.

4—5 designate the usual post terminals or short posts in electric connection with the base 6 of the iron and onto which the circuit closing devices are mounted, the peculiar construction of which and the means for effecting the positions thereof, constitute the essential feature of this invention.

7 designates the plug casing which has the usual sockets for slidably engaging the post or terminals 4 and 5. The casing 7, which is composed of the usual insulation material, in my construction, has a central supplemental socket or chamber 70 which extends practically the full length thereof and which, at the side adjacent the rear one 8 of the handle brackets, is open, as at 71, for the free play of a plunger device, which device, at predetermined times, as presently stated, pushes the circuit closing element 11 to the circuit closing position, indicated in full lines in Figure 2.

Referring now particularly to Figures 2 and 3 of the drawings, it will be noticed that one (9) of the electric current wire leads 9—90 joins with a contact member 10 that

is fixedly held in the outer wall of the casting 7 and with which the wire 9 joins, as is clearly shown in full lines on Figure 2 and in dotted lines Figure 3.

- 5 The plunger device, before referred to, consists of a rod 21, the rear end of which is shod with an insulating cap 22 for engaging a knife blade switch member 11, said rod 21, is slidably mounted in a long sleeve bearing 12^a on a hanger bracket 12 which is secured to the rear end of the handle 1 by a screw rod 13 and nut 14 its forward end is adjustably connected to a shifting head block 15 which is upwardly and forwardly bevelled and has a pendent lip 15^a, the reason for which will appear later.

10 The knife blade switch lever 11, shown in detail in Figure 4, consists of a long arm-like member bifurcated and apertured at the lower end for pivotally engaging with a bracket bearing 16 that is detachably mounted within the lower end of the central socket or chamber 70 of the casing 7, by a clamp nut 17.

15 The switch lever 11 includes a head 18 that is provided with a knife contact 19 adapted to engage a like face in the head of the fixed contact 10 when it is bodily moved by the shifting head block 15 in the direction indicated by the arrow on Figure 2, the said switch lever being normally swung back to the open or circuit breaking position, shown in dotted lines, Figure 2, 20 by a coil spring 20 which engages a seat in the casing socket 70, as shown.

25 It is to be noted the plunger rod 21 has a threaded connection with the head block 15 to provide for making delicate adjustment of the parts when necessary.

30 The lead wire 9 from the cord connects with the fixedly held contact member 10, as before stated, and the other lead 90 joins directly with the right hand contact sleeve 45 which engages the post 5, and since the said lever 11 is in electrical connection with the left hand sleeve or post 4, as indicated by 23 on Figure 3, it follows that as the contact lever 11 is swung over to its full line 50 position, as shown in Figure 2, the current is caused to pass through the lever to the left hand post 4 and thereby complete the current through the iron which will then be heated for use.

55 It will be clearly apparent, from Figure 2, that the normal position of the current closing devices is at the current breaking or open position, and therefore so long as the iron is left to stand free there will be 60 no current passed to it and hence it remains cold.

65 For shifting the contacting member 11 to the closed position, and that without any especial attention or effort of the user, I provide an auxiliary handle member that

is preferably of some non-heat absorbing material, and which includes a finger engaging portion 35 which has the contour of the adjacent main handle portion and the inwardly projecting (preferably wooden) 70 flange 36 that extends the full length of the said auxiliary member and which has free movement, up or down, within the longitudinal socket 2 in the bottom of the main handle 1, the metal liner, before referred to, 75 preventing binding of the parts and facilitating the free rise or drop of the said members 35-36.

80 The auxiliary handle has a loose pivotal connection 38 at the front of the bottom of the main handle, so that as the user grasps the handle the auxiliary member will be caused to swing upwardly from the position shown in dotted lines to the full line position, as indicated in Figure 2.

85

85 It is this movement of the said auxiliary handle, in the forward direction, that causes the switch lever 11 to shift over to the full line or circuit closing position, which is provided for, by reason of the 90 heel 39 of the auxiliary handle engaging the bevelled face of the head plug 15, it being obvious that when the grip member 35 is pressed upwardly, as a user grasps the handle 1, the said part 39 will force the 95 head 15, together with its plunger pin 21, in the direction of the arrow and thereby move the switch 11 to the closed position, against the tension of the thrust back spring, which position of the parts is maintained so long as the user grasps the handle 1.

100 Should, at any time, the user release the grip on the handle, the auxiliary member 35-36 would instantly swing down to the full line position in Figure 1, and the dotted position on Figure 2, and thus permit the spring 20 to throw the switch lever 11 back to the dotted or circuit broken position, thereby cutting out the source of heat from the iron.

110

110 To provide for readily holding the parts to their circuit closing position at times when it is desired to continue to heat the iron, and particularly when it is desired to "heat up" a cold iron, I provide a simple loop shaped catch 55 that pivotally engages the bracket bearing and is adapted for being pivotally swung over the lower or lip portion 15^a of the head block 15, as shown in dotted lines on Figure 2, it being obvious that the spring tension that forces the switch lever and the plunger outwardly, will continue the locking engagement of the parts and thus provide for maintaining current through the 125 iron for heating it when the grip member 35 is at the dropped or dotted position shown in Figure 2.

115

125 In practice the plunger 21 has sufficient play within the long bearing 12^a, so that, 130

when the operator grasps the handle and moves member 35 up against the head block 15 there is sufficient vertical play of the plunger rod 15 to thereby automatically release the catch 55 which then assumes its pendent or normal position, as indicated in full lines in Figures 2 and 5 and thus provides for free movement of the parts 15-15* for shifting the switch lever 11 to the circuit closing or opening position.

As more or less pressure is imparted to the plug casing 7 in the shifting of the plunger 21, I provide a simple means for locking the block against disarrangement under such pressure, such means comprising an angled member 65 that is attached to the head of the block and adapted to engage a flanged keeper 75 that is held onto the adjacent end of the handle, as shown.

From the foregoing description, taken in connection with the drawing, the complete construction, the manner of operation and the advantages of my invention will be readily apparent to users of electric irons.

My improvement provides for positively cutting out the electric current whenever the user releases the iron, thereby effecting much saving in the use of the current and overheating the iron and avoids burning the article on which the iron may be resting.

While the means shown and described, illustrate a simple and practical way of accomplishing the desired stated results I desire it understood that I do not limit myself to the exact arrangement of the parts and the details shown and described, since they may be readily varied or modified to suit the particular pattern of electric iron to which my invention may be adapted, without departing from the broad features of my said invention as comes within the scope of the appended claims.

What I claim is:

1. In an electric iron having post terminals and a handle, the combination in a plug having electrically connected sockets for slidably engaging said post terminals, of an elongated central chamber, a knife switch pivotally attached in the lower end thereof and having electrical connection with one socket, a knife contact element rigidly attached in the upper end thereof and having electrical connection with the other socket

and coordinately positioned with the knife element of said knife switch, a spring adapted to hold the head of the knife switch away from the knife contact element and means on the handle of said iron for operating said knife switch against said spring to make electrical contact for the purpose described. 55

2. In an electric iron having a handle and post terminals the combination of an electrically connected plug having a knife switch and means for slidably engaging said post terminals, an auxiliary handle for operating a movable head block and plunger adapted to operate a knife switch in said plug and make electrical connection to the heating elements of said iron, a partly circular ring member pivotally attached to the 70 sleeve bearing of said head block plunger and a lip on said head block whereby said ring may hold said plunger against the knife switch in aforesaid plug for the purpose described. 75

3. The combination with a sad iron having the usual terminals for engaging with a circuit connecting plug; the said plug having the electric wire leads secured thereto, a fixed contact in connection with one of the 80 wire leads, and a switch member normally held out of engagement with the aforesaid contact and, in connection with the other wire lead, and means comprising an auxiliary member attached to the handle of the 85 iron and adapted for being gripped as the user takes hold of the handle of the iron and for being moved toward the said handle, and a member shiftable by the said movement of the said auxiliary handle member and 90 adapted when shifted to move the switch member into engagement with the aforesaid contact and thereby close the current from the supply to the iron for heating it.

4. In an electric iron, a circuit closer including a pivoted contact making switch, means tending to normally hold the switch to the open position for cutting out the electric current to the iron, a plunger member engaging the free end of the said switch and a movable member attached to the iron adapted when the handle of the iron is grasped to effect movement of the plunger whereby to move the contact making switch to the circuit closing position. 95

AMBROSE FLEMING.
